UNITED STATES PATENT OFFICE.

JOSEPH S. BUSHEY, OF LOS ANGELES, CALIFORNIA.

AXLE-SETTING APPARATUS FOR AUTOS.

Application filed February 17, 1926. Serial No. 88,838.

This invention relates to apparatus for setting or adjusting the front axles of automobiles to regulate the amount of cant or camber of the wheels carried by the axle. 5 In this art the term "camber" has come to mean the inclination of the plane of the front wheels from the vertical plane extending in a front and rear direction.

The general object of the invention is to 10 provide simple apparatus for this purpose which can be quickly rigged up in position for operation and which can be used readily for increasing the camber or for reducing the camber.

15 A further object of the invention is to provide apparatus of this kind which enables the axle to be set while in place on the car and without disturbing any of the parts carried by the axle.

20 The invention contemplates the use of jacks or similar devices for enabling the axle to be subjected to a bending moment in the desired direction, and one of the objects of the invention is to construct the apparatus 25 in such a way as to facilitate the cooperation of these jacks with a pair of slings which suspend the apparatus from the axle, the slings being constructed in such a way that they can be shifted to cooperate with the 30 jacks in the different uses of the apparatus without necessitating making any connections or disconnections of the slings.

Further objects of the invention will appear hereinafter.

35 The invention consists of the novel parts and combination of parts to be described hereinafter, all of which contribute to produce an efficient axle-setting apparatus for an automobile.

40 A preferred embodiment of the invention is described in the following specification, while the scope of the invention is pointed out in the appended claims.

In the drawing:

45 Fig. 1 is a front elevation illustrating the front axle of an automobile and illustrating the apparatus applied to the same with the parts in the relation which they have when reducing the camber in the wheels;

50 Fig. 2 is a view similar to Fig. 1, but showing the apparatus organized for increasing the camber in the wheels;

55 Fig. 3 is a vertical section taken through the front axle and through the body or bar of the apparatus at one of the jacks which cooperate with the slings; and

Fig. 4 is a plan showing one end of the body or bar of the device broken away.

In practicing the invention I provide a rigid strong-back or bar 1 which preferably 60 consists of a stout solid bar of rectangular cross-section. I provide means for suspending this bar from the front axle 2 of the automobile. For this purpose I prefer to provide two slings 3 which are constructed 65 in such a way that they engage under the bar 1 to support it, but are preferably not secured to the bar, and hence they can be shifted longitudinally of the bar without disconnecting any fastenings. 70

Each of the slings 3 is preferably in the form of an inverted U-bolt or U-bar hung over the axle; the lower ends of the arms are formed, respectively, with eyes 4 which receive a cross-pin or bolt 5. These bolts or 75 pins 5 extend under the bar 1 and support the bar.

In Fig. 1 I illustrate the apparatus arranged for setting the axle in a direction to reduce the camber or inclination of the 80 wheels, but the apparatus is equally capable of use for increasing the camber, as illustrated in Fig. 2.

In order to enable the apparatus to be equally useful for both of these purposes, I 85 provide the upper side of the bar 1 with a plurality of jack-seats, each jack-seat being preferably in the form of a deep socket 6. In forming these sockets they are counter-bored so as to form a depressed annular 90 shoulder 7 toward the lower face of the bar.

I provide a plurality of jacks 8, each jack consisting of an internally threaded sleeve 9 which is received in the socket or seat 6 (see Fig. 3), so that the lower end rests upon 95 the annular shoulder 7. Each sleeve is provided with a key 10 which is received in a key-slot 11 to prevent the sleeve from rotating when the screw 12 is rotated. Each screw has a head 13 with a swiveled saddle 100 plate 14 at its upper end which seats against the under side of the axle. The head 13 is provided with a plurality of sockets 15 which may receive the end of a lever as indicated in dotted lines at 16 in Fig. 3. A lever of considerable length can be inserted

and gives sufficient leverage to screw up or unscrew the jacks. Two of these jack-seats 6 are located respectively at the ends of the bar, and I provide two or more intermediate 105 jack-seats, the arrangement being such as to enable the jack-screws to be located toward

the ends of the bar when the slings are located near the middle of the axle, and vice versa.

I prefer also to provide one of the jack-seats at the middle point of the bar. This enables a middle jack to be used in arranging the apparatus for operation. This middle jack is not used to exert any great force upon the axle but is simply tightened up so as to bring the bar 1 into proper alignment with the "vertical plane" or web of the axle. By providing this middle jack and tightening it first there is no danger that when the outer jacks are tightened up there will be any tendency to twist the axle or bend it in any plane except the plane of its web.

In using the apparatus to increase the camber in the wheels 17, I simply shift the slings 3 out to a point near the ends of the bar 1, and I move the jacks 8 from the position in which they are illustrated in Fig. 1 into a pair of symmetrically located jack-seats (see Fig. 2). With the apparatus arranged in this way, by tightening up the jacks it will be evident that a bending moment can be exerted on the axle which will bend it or set it in a direction to increase the camber of the wheels.

When using the apparatus the front end of the automobile may be supported on two blocks set under the wheels (see Fig. 1), and one of the blocks may be on rollers to facilitate the altering of the relative positions of the wheels when the axle is set to its new form.

What I claim is:

1. In an apparatus for setting the front axle of an automobile, the combination of a rigid bar, a pair of slings engaging under the bar, and movable along the bar, for suspending the same from the axle, and jacks supported on the bar on opposite sides of the slings for exerting upward pressure against the under side of the axle at different points with respect to the slings.

2. In an apparatus for setting the front axle of an automobile to adjust the camber of the wheels, the combination of a rigid bar, a pair of slings engaging under the bar and movable along the bar for suspending the

same from the axle, said bar having jack-seats adjacent the ends of the bar and a jack-seat at an intermediate point on the length of the bar, and jacks capable of being received in the jack-seats and cooperating with the slings when the slings are located near the middle of the axle to bend the axle in a direction to take the camber out of the wheels, and capable of cooperating with the slings when the slings are located at the ends of the bar to bend the axle in a direction to increase the camber of the wheels.

3. In an apparatus for setting the front axle of an automobile to adjust the camber of the wheels, the combination of a rigid bar, a pair of slings consisting respectively of U-bolts hung over the axle with cross-pins at their lower ends passing under the bar, said slings being movable along the bar and operating to suspend the same from the axle, said bar having a plurality of sockets in its upper face operating as jack-seats, a plurality of jacks having internally threaded sleeves received in said sockets, said jacks having heads to seat against the under side of the axle.

4. In an apparatus for setting the front axle of an automobile, the combination of a rigid bar, means for supporting the bar from the axle toward one side of the automobile, means for supporting the bar from the axle at a point toward the other side of the automobile, and a jack corresponding to each of said means and capable of being mounted on either side of the same to exert pressure against the under side of the axle.

5. In an apparatus for setting the front axle of an automobile, the combination of a rigid bar, a pair of slings engaging under the bar and movable along the bar for suspending the same from the axle, and a pair of jacks, each corresponding to each sling supported on the bar and cooperating with the same for exerting upward pressure against the under side of the axle, the slings being capable of being positioned outside the jacks, or between the jacks, as desired.

Signed at Los Angeles, Calif., this 9th day of February, 1926.

JOSEPH S. BUSHEY.
